[57] CLAIM

The ornamental design for a dresser with mirror, as shown and described.

DESCRIPTION

FIG. 1 is a perspective view of a dresser with mirror
showing my new design;

FIG. 2 is a front elevational view thereof;

FIG. 3 is a side elevational view thereof, the opposite side being a mirror image of the side shown; and,

FIG. 4 is a top plan view thereof.

The rear of the dresser with mirror is flat and unornamented.
